DISPENSER FOR BOTTLE

Peter P. Bazarnic, 12200 Grannis Road, Cleveland, Ohio

Filed June 22, 1964, Ser. No. 80,521

Term of patent 14 years

(Cl. D58—26)

FIG. 1

FIG. 3

FIG. 4

FIG. 5

FIG. 1 is a side elevational view of a dispenser for bottle embodying my new design;

FIG. 2 is a top plan view thereof;

FIG. 3 is a rear elevational view thereof;

FIG. 4 is a front elevational view thereof; and

FIG. 5 is a bottom plan view thereof;

The dominant features of my design reside in the portions shown in full lines.

I claim:

The ornamental design for a dispenser for bottle, as shown and described.
